UNITED STATES PATENT OFFICE.

PAUL ZWIJACZ, OF CHICAGO, ILLINOIS.

ROCKING-CHAIR.

1,358,274.

Specification of Letters Patent. Patented Nov. 9, 1920.

Application filed March 24, 1920. Serial No. 368,308.

To all whom it may concern:

Be it known that I, PAUL ZWIJACZ, a citizen of Poland, residing at Chicago, in the county of Cook and State of Illinois, have 5 invented certain new and useful Improvements in Rocking-Chairs, of which the following is a specification.

This invention relates to certain new and useful improvements in rocking chairs and 10 has particular reference to the provision of simple and efficient means for enabling the occupant of the chair to produce, by foot operation, cooling blasts of air in hot weather.

15 The invention broadly contemplates the provision of a foot actuated bellows suitably connected with a vertically disposed perforated outlet pipe which is centrally arranged between the vertical rungs of the chair back 20 with its perforations disposed so as to allow passage of air therefrom onto a person's back and head.

With the above general objects in view and others that will appear as the nature of the 25 invention is better understood, the same consists in the novel form, combination and arrangement of parts hereinafter more fully described in connection with the accompanying drawing.

30 In the drawing wherein like reference characters indicate corresponding parts throughout the several views.

Figure 1 is a side elevational view of a 35 rocking chair constructed in accordance with the present invention, partly broken away.

Fig. 2 is a front elevational view thereof, partly broken away,

Fig. 3 is a transverse sectional view taken substantially upon line III—III of Fig. 1,

40 Fig. 4 is a vertical sectional view taken substantially upon line IV—IV of Fig. 2, and

Fig. 5 is an enlarged sectional view taken substantially upon line V—V of Fig. 2.

45 Referring more in detail to the several views, the present invention comprises a rocking chair having the ordinary bottom or seat 5 rigidly secured to the four supporting legs 6 which have the arm rests 7 secured 50 upon the upper ends thereof and which are braced by suitable rungs 8. The lower ends of the legs 6 are fastened to suitable rockers which are of laminated form comprising an upper wood layer 9, two rubber layers 10 therebeneath, and a metallic layer 11 between the rubber layers, secured together by

any suitable fasteners such as indicated at 12. This form of rocker will be substantially noiseless and provide a cushion effect during the rocking operation. 60

The upper member 13 of a bellows is rigidly fastened beneath the chair seat 5 and its lower member 14 is hinged as at 15 for movement toward and away from the member 13 thereof in the usual manner. The 65 lower member 14 of the bellows is provided with the usual inlet flap valves 16, and the bellows is open at its rear edge in communication with a manifold 17 formed by a transverse tubular rung positioned at the rear edge 70 of the seat 5. The manifold 17 is connected at its ends to another tubular horizontal manifold 18 positioned above the same by providing passages in the adjacent portions of the side rails 19 of the chair back as indicated at 20 in Fig. 2, and the manifold 18 constitutes the lower rail of the chair back 75 and is connected to the top rail 21 thereof by the usual slats or bars 22.

An outlet pipe 23 communicates with the 80 central portion of the upper manifold 18 and extends upwardly from the latter. The outlet pipe 23 is provided with a cross head 24 at its upper end and this head is seated in a groove provided in the front face of the 85 upper rail 21 of the chair back as shown in Fig. 5. The outlet pipe 23 and its head 24 is provided with a number of perforations 25 so as to permit the passage of air there- 90 through onto the person's back and head occupying the chair and manipulating the bellows as will presently be described.

The rockers of the chair are connected by a horizontally disposed rod 26 extending transversely therebetween, and a foot lever 95 having end hubs 27 journaled upon the rod 26 is provided with rearwardly extending arms 28 which are slidably and pivotally connected to the lower hinged member 14 of the bellows by pin and slot connections 29. 100 This foot lever includes a treadle or pedal 30 which extends forwardly from the hubs 27 in convenient position for receiving the feet of the occupant of the chair whereby the foot lever may be rocked for actuating the 105 bellows as will be apparent.

It will be seen that when the pedal 30 is moved downwardly the arms 28 will be swung upwardly for moving the lower bellows members 14 toward the stationary 110 member 13 thereof, thereby forcing air into the manifolds 17 and 18 to the outlet pipe 23

and through the perforations 25 thereof. This will effectively serve to cool the occupant of the chair in warm weather without the necessity of employing expensive electrical fans or the like.

It is believed that the construction and operation of the present invention will be readily understood and the advantages thereof appreciated from the foregoing description.

10 Minor changes may be made without departing from the spirit and scope of the invention as claimed.

What I claim as new is:—

- 15 1. A rocking chair including a seat member having supporting legs provided with rockers, a back for said chair comprising vertical slats and horizontal upper and lower rails connected thereby, said upper rail being centrally recessed, the lower rail consisting of a tubular manifold, a bellows beneath the seat member and interiorly connected with the interior of said lower rail, an outlet pipe for air from the bellows connected with the interior of said lower rail at the center of the latter and extending upwardly therefrom, said outlet pipe having perforations therethrough, means for actuating said bellows, a cross head upon the upper end of said outlet pipe seated in said recess of the top rail and having perforations therethrough, said bellows actuating means including a foot rest pivoted to the rockers, 50 said bellows including a vertically swingable lower member, and a pair of rearwardly extending arms rigid with the foot rest and slidably and pivotally connected to said swingable bellows member.
- 20 2. A rocking chair including a seat member having supporting legs provided with rockers, a back for said chair comprising vertical slats and horizontal upper and lower rails connected thereby, said upper rail being centrally recessed, the lower rail consisting of a tubular manifold, a bellows beneath the seat member and interiorly connected with the interior of said lower rail, an outlet pipe for air from the bellows connected with the interior of said lower rail at the center of the latter and extending upwardly therefrom, said outlet pipe having perforations therethrough, means for actuating said bellows, and a cross head upon the upper end of said outlet pipe seated in said recess of the top rail and having perforations therethrough.
- 25 3. A rocking chair including a seat member having supporting legs provided with rockers, a back for said chair comprising vertical slats and horizontal upper and lower rails connected thereby, said upper rail being centrally recessed, the lower rail consisting of a tubular manifold, a bellows beneath the seat member and interiorly connected with the interior of said lower rail, an outlet pipe for air from the bellows connected with the interior of said lower rail at the center of the latter and extending upwardly therefrom, said outlet pipe having perforations therethrough, means for actuating said bellows, and a cross head upon the upper end of said outlet pipe seated in said recess of the top rail and having perforations therethrough.

said recess of the top rail and having perforations therethrough.

2. A rocking chair including a seat member having supporting legs provided with rockers, a back for said chair comprising vertical slats and horizontal upper and lower rails connected thereby, said upper rail being centrally recessed, the lower rail consisting of a tubular manifold, a bellows beneath the seat member and interiorly connected with the interior of said lower rail, an outlet pipe for air from the bellows connected with the interior of said lower rail at the center of the latter and extending upwardly therefrom, said outlet pipe having perforations therethrough, means for actuating said bellows, a cross head upon the upper end of said outlet pipe seated in said recess of the top rail and having perforations therethrough, said bellows actuating means including a foot rest pivoted to the rockers, 50 said bellows including a vertically swingable lower member, and a pair of rearwardly extending arms rigid with the foot rest and slidably and pivotally connected to said swingable bellows member.

55 In testimony whereof I affix my signature.

PAUL ZWIJACZ.
